SNAP ACTION PULL TABS
 Charles F. Hutcheson, 192 Shepherd Lane,
 Roslyn Heights, N.Y.
 Filed June 12, 1963, Ser. No. 287,308
 5 Claims. (Cl. 215--51)

This invention relates to tabs, and more particularly to such tabs as used for opening disc and other closures.

Tabs are provided in a variety of containers for obtaining a grip with the fingers so as to permit removing a disc or other closure member, or for grasping of a tear strip. Where the tab lies sufficiently flat to prevent accidental opening of the container or damage to the tab, difficulty in grasping it exists and it is the general object of the present invention to provide a pull tab which is not subject to this objection.

The tab construction of the invention consists in a strip fastened at one end, free at the other and normally lying flat, the strip material being of sufficiently inextensible character so as to buckle when distorted in two planes of curvature, the tab having a convexly domed portion which when depressed buckles so as to become concave, thus lifting the tab end for ready grasping.

A tab construction embodying the invention in a preferred form will now first be described with reference to the accompanying drawing, and the features forming the invention will then be pointed out in the appended claims.

In the drawing:

FIG. 1 is an isometric view of a milk bottle with closure according to the invention;

FIG. 2 is a plan view on an enlarged scale of the closure of FIG. 1;

FIG. 3 is a section on the line 3--3 of FIG. 2;

FIG. 4 is a view similar to FIG. 3 but showing the tab in elevated position; and

FIGS. 5 and 6 are views similar to FIGS. 2 and 3, showing a modified form of the invention.

Referring now to FIGS. 1, 2 and 3, a milk bottle 1 is shown as provided with a closure 2 seating in the pouring opening of the bottle in the usual manner. As usual, the bottle neck opening has a wider part 3 where the disc seats, the inner surface 4 above this being slightly flared downwardly and outwardly so that the closure disc 2 snaps in position and effort is required to remove it.

The pull tab 5 of the invention may be secured to the element with which associated in any convenient manner, or may be formed integral therewith. In the construction shown, the tab 5 is secured at one end to the disc 2 by a staple 6. Adjacent the free end 7 of the tab, it is formed with an upwardly convex dome 8, pressure on which causes it to buckle downwardly (so as now to be upwardly concave) thus lifting the end 7 of the tab into position for convenient grasping by the fingers as shown in FIG. 4.

The tab of the invention may be made of any of a variety of materials, including synthetic resins of various types and also metals. It is necessary only that the material have sufficient flexibility (when bent in one plane of curvature) and inextensibility, so as to buckle in the manner described. In the specific type of milk bottle tab shown, polypropylene film in a thickness of .010 inch is satisfactory.

The member by which the tab is carried or on which it rests may be indented as shown in FIGS. 5 and 6. These figures indicate a closure disc 12 generally like the

2

disc 2 of FIGS. 1-4, with tab 15 secured to it by staple 16, the free end 17 of the tab having a dome 18 operating similarly to the dome 8 just mentioned. The disc 12, however, is formed with a depressed area 20, accommodating the tab (which depression may be made deep enough so as to bring even the top of the dome 18 flush with the surface of member 12). The action is otherwise the same as above described.

What is claimed is:

1. A pull tab element for opening container closures, comprising a strip secured at one end to the closure, a free end and an upwardly convex dome adjacent the free end, the strip material being flexible when bent in a single plane of curvature but substantially inextensible, whereby pressing down on the dome causes the same to buckle, becoming upwardly concave and lifting the free end into position for grasping.

2. A pull tab element for opening container closures, comprising a strip secured at one end to the closure, a free end lying substantially flat against the container closure surface and an upwardly convex dome adjacent the free end, the strip material being flexible when bent in a single plane of curvature but substantially inextensible, whereby pressing down on the dome causes the same to buckle, becoming upwardly concave and lifting the free end into position for grasping.

3. A pull tab element for opening container closures, comprising a strip secured at one end to the closure, a free end lying substantially flat against the container closure surface and an upwardly convex dome adjacent the free end, the strip material being flexible when bent in a single plane of curvature but substantially inextensible, whereby pressing down on the dome causes the same to buckle, becoming upwardly concave and lifting the free end into position for grasping, the container closure surface having a depression accommodating the strip so that the free end of the strip is below the level of the surrounding surface generally.

4. A pull tab element for opening container disc closures, comprising a strip secured at one end to the closure disc, a free end lying substantially flat against the disc and an upwardly convex dome adjacent the free end, the strip material being flexible when bent in a single plane of curvature but substantially inextensible, whereby pressing down on the dome causes the same to buckle, becoming upwardly concave and lifting the free end into position for grasping.

5. A pull tab element for opening container disc closures, comprising a strip secured at one end to the closure disc, a free end lying substantially flat against the container closure surface and an upwardly convex dome adjacent the free end, the strip material being flexible when bent in a single plane of curvature but substantially inextensible, whereby pressing down on the dome causes the same to buckle, becoming upwardly concave and lifting the free end into position for grasping, the disc surface having a depression accommodating the strip so that the free end of the strip is below the level of the surrounding surface generally.
